UNITED STATES PATENT OFFICE.

HOLDEN P. BALLOU, OF HARTFORD, CONNECTICUT, ASSIGNOR TO WALTER S. SCHUTZ,
TRUSTEE, OF HARTFORD, CONNECTICUT.

PNEUMATIC PIANO-PLAYER.

1,136,923.

Specification of Letters Patent.

Patented Apr. 27, 1915.

Application filed January 31, 1913. Serial No. 745,360.

To all whom it may concern:

Be it known that I, HOLDEN P. BALLOU, a citizen of the United States, residing at Hartford, in the county of Hartford and State of Connecticut, have invented certain new and useful Improvements in Pneumatic Piano-Players, of which the following is a specification.

This invention relates to pneumatic piano-players, among the principal objects of the invention being the simplification in construction of the action itself and the accessibility of the "bleeds" associated with the secondary chambers or equivalent parts of the apparatus.

In the drawings accompanying and forming part of the present specification I have shown in detail one of the several advantageous forms of embodiment of the invention which to enable those skilled in the art to practice the same will be fully set forth in the following description. I may depart from this showing in several respects within the scope of the invention defined by my claims.

Referring to said drawings: Figure 1 is a cross sectional view of a piano player involving my invention, and, Fig. 2 is a front elevation of one end of the same.

Like characters refer to like parts in both figures.

A pneumatic player action comprises a chest as 2 and certain accessories hereinafter more particularly described. In the actions or chests of pneumatic piano players, it has been the general custom heretofore to provide a number of main vacuum chambers and a corresponding number of auxiliary vacuum chambers, each auxiliary chamber coöperating with a main chamber. This is complex. I simplify the construction by providing several auxiliary chambers in number at least equaling the notes to be played, but only provide one main chamber, this main chamber being common to all the auxiliary chambers which are used in the playing of the keys, and a main chamber such as meets the desired conditions, is that denoted by 3 being approximately coextensive with the chest 2. The auxiliary chambers are denoted by 4, and they may be related with the main chamber in any desirable way, although they are illustrated as situated above the same. The auxiliary chambers 4 operate in connection with a

tracker as 5, which after the usual fashion is perforated. From the tracker to the respective auxiliary chambers 5 the ducts 6 extend uninterruptedly, so that after the customary manner each auxiliary chamber 4 60 is connected by a duct or tube 6, with a hole, slot or perforation in the tracker 5, by virtue of which when one of these holes or perforations is uncovered by the music sheet, atmospheric air passing through said hole, 65 enters the duct 6 leading therefrom and into the coöperating auxiliary chamber 4 to effect in the usual way or otherwise action of the appropriate pneumatic.

The pneumatics are denoted by 7 and as 70 represented are of "bellows" type and as suitably fastened to the underside of the chest 2. Said chest has channels or passages 8, there being one of each for the pneumatics 7 and auxiliary chambers 4. Ducts such as 75 tubes 9, of metal or other suitable material, extend from the respective channels 8 to the respective pneumatics 7. Each of the channels 8 is connected with the main vacuum chamber 3, by a port 10 governed 80 by a valve as 11 fastened to a rod or stem as 12 guided by flanges as 13 fastened to a cleat 14 united with the roof of the main chamber 3. The stems of the valves project through the respective ports 10, through the 85 channels or passages 8 and also through ports or openings 15 extending from the respective passages 8, being provided with diaphragms marginally fastened around the open under sides of the respective auxiliary 90 chambers 4.

It will be supposed that an opening in the tracker 5 is uncovered by the music sheet in which event atmospheric air passes through said opening into the appropriate 95 duct or tube 6 coöperative therewith and into the auxiliary chamber 4 into which said duct opens, thus forcing the corresponding diaphragm 16 downward, opening the valve 11 associated therewith and putting the 100 main chamber 3 into communication with the coöperating pneumatic 7 by way of a channel 8 and duct or tube 9 to thus operate said pneumatic and hence the key connected therewith. In practice the main chamber 3 105 will be connected with a suitable vacuum producing device, such as a pump (not shown), a suction pipe 17 leading from said main chamber 3 to the pump.

The chest 2 has in addition to the exhaust 110

or vacuum chambers already described, a bleed exhaust chamber 20 which as illustrated is located at the front and near the upper side and although this particular disposition is not essential it is highly advantageous in that it provides for the ready accessibility of the bleed openings hereinafter described. It is usual in a pneumatic player, to provide "bleeds" as they are known, the function of which is to positively cause suction to maintain the valves closed by acting on the diaphragms of the respective valves. These bleeds have been ordinarily quite inconvenient to reach, being inclosed within the action so that to get at them it is necessary to dismount certain of the parts of said action. I am familiar with another mode of "bleeding" wherein the bleed openings are exterior of the action being in the tubes which lead from the tracker. This construction is not so good as it is necessary to make these tubes in sections thereby making a number of joints and increasing the liability of leakage. In the present construction the tubes from the tracker are continuous or unbroken. The chamber 20 may be exhausted in any desirable way; for this purpose I have shown the pipe 21 which connects said bleed exhaust or vacuum chamber 20 with the main vacuum or exhaust chamber 3. From the auxiliary chambers 4, the passages 22 extend, the diaphragm valves 23 being situated at the upper ends of said passages and being coöperative with coupling chambers 24 which constitute the subject matter of my application Serial No. 679,841 filed February 26, 1912. Connecting these passages 22 with the bleed exhaust or vacuum chamber 22 are the ducts 25 which as shown, consist of nipples or short tubes the outer ends of which project into said chamber 20. The rounded forward ends of said tubes 25 have small perforations or holes 26 which are the bleed openings, said bleed openings or holes being horizontally alined so that when necessary they can be readily cleaned of accumulations of dirt and like particles by merely sweeping across them with a brush. As is the case with other constructions the bleed openings are smaller than the openings in the tracker.

The bleed chamber has a door or flap 27 which as illustrated is hinged along its under edge by a flexible hinge, such as of leather 28, to the chest 2 immediately below said chamber, said door being opened by a downward, forward swing although this particular relation is not always necessary. Said door has in its upper edge a notch or slot 29 through which the stud 30 on the chest 2 extends, said stud being threaded to receive the holding nut 31 which when set securely holds said door in a closed position to properly maintain the vacuum in said chamber 20. To open the door the nut is loosened and the door then slightly lowered to carry it clear of said nut, and then swung forward and down, to thereby reach said bleed openings 26. There may if necessary, be interposed between the door and the chest, some suitable packing.

What I claim is:

1. A vacuum chest having a vacuum bleed chamber directly therein, bleed openings extending into said vacuum chamber, the latter being open on one side, an air-tight closure for the bleed chamber, and means for holding the closure in place.

2. A vacuum chest having a vacuum bleed chamber directly therein, bleed openings extending into said vacuum chamber, the latter being open on one side, an airtight closure for the bleed chamber, and means for removably holding said closure in place.

3. A vacuum chest having pneumatics, means embodying auxiliary chambers, a tracker in communication with said auxiliary chambers, and diaphragms associated with the respective auxiliary chambers, for controlling said pneumatics, said chest having an exteriorly accessible bleed chamber directly therein, and nipples communicating with the respective auxiliary chambers, extending into said bleed chamber, the forward ends of said nipples having bleed openings.

In testimony whereof I affix my signature in presence of two witnesses.

HOLDEN P. BALLOU.
